UNITED STATES PATENT OFFICE.

RICHARD M. FOSTER, OF WORCESTER, MASSACHUSETTS, ASSIGNOR TO THE HASTINGS & MCINTOSH TRUSS CO., OF PHILADELPHIA, PENNSYLVANIA, A CORPORATION OF PENNSYLVANIA.

FEED CONTROL FOR KNITTING MACHINES.

Application filed April 23, 1923. Serial No. 633,979.

My invention relates to knitting machines, particularly of the circular latch needle type, adapted for knitting tubular ribbed seamless articles, such as elastic stockings, knee caps, and other knitted seamless elastic goods for surgical and other purposes.

In the knitting of seamless elastic goods, the shape of the article is altered by varying the length of the elastic thread fed to the machine, relatively to the circumference of the needles, and the object of the present invention is to provide an improved mechanism for controlling the feed of the elastic thread, whereby any desired length of elastic thread can be positively measured and fed to the machine for each course knitted thereby. My invention contemplates an improved mechanism for controlling the rotation of the rolls which feed the elastic thread, whereby the latter are driven independently of the rotation of the knitting head. In this respect my improved machine differs fundamentally from similar machines heretofore constructed, in which the elastic thread feeding mechanism rotates with the knitting head, thereby resulting in undesirable complication of parts and operating difficulties. My invention also contemplates elastic thread feeding rolls which are adapted to feed the elastic a predetermined, unvarying distance for each revolution thereof, thereby resulting in a feed mechanism susceptible to quick, positive variation.

The above and other advantageous features of my invention will hereinafter more fully appear, reference being had to the accompanying drawings in which—

Fig. 1 is a view in front elevation of a circular knitting machine provided with my improved feeding mechanism for the elastic thread.

Fig. 2 is a plan view of the parts shown in Fig. 1.

Fig. 3 is an enlarged end view of a portion of the parts shown in Fig. 1, illustrating the details of my improved mechanism.

Fig. 4 is a plan view of the parts shown in Fig. 3.

Fig. 5 is an enlarged view of a portion of the parts shown in Fig. 1.

Fig. 6 is a fragmentary view, showing on an enlarged scale, the relation of my improved feeding rolls to the knitting head.

Like reference characters refer to like parts in the different figures.

Referring first to Figs. 1 and 2, there is shown a knitting machine adapted for the manufacture of circular seamless elastic goods, which comprises a fixed needle cylinder 1 having stationary sets of needles, a ribber dial 2, a cam cylinder 3, and a cam plate 4. The machine also comprises a knitting thread guide 5 to which the knitting threads 6 are led from suitable spools 7, and an elastic thread guide 8 to which elastic thread 9 is fed from a suitable magazine 10 by a pair of feed rolls 11 and 12, the guides 5 and 8 and the spools 7 revolving with the cylinder 3 beneath the rolls 11 and 12. Take-up rolls 13 are provided below the knitting head for pulling down the work as it is knit by the machine.

The above described arrangement of the parts of the knitting head forms no part of my present invention and the knitting head is adapted to operate in substantially the same manner as in other similar circular knitting machines. In the manufacture of knitted elastic hosiery by machines of the type illustrated in the drawings, the elastic thread 9 is laid into the work and held therein by knitted loops formed by the knitting threads 6, and if the length of the elastic thread 9 fed to the needles for any given

course is the same as the circumference of the needles, then the knitted article is of the same diameter as the needle cylinder. If, however, the elastic thread 9 is stretched as it is knitted into a course, then after the fabric has left the needles, the elastic thread contracts and thus reduces the diameter of the fabric produced. In my improved machine, the elastic thread 9 is positively fed

by the rolls 11 and 12, a fixed distance for each revolution thereof, and my invention relates to rolls so designed and to improved mechanism driving the rolls, whereby the rate of feed of the elastic thread by the rolls 11 and 12 is automatically varied to control the shape of the fabric, as will now be described.

The feed rolls 11 and 12 are each rotatably supported at the end of a bracket 14 extending upwardly from a table 15 and overhanging the knitting head. The rolls 11 and 12, it will thus be noted, are on fixed axes. The bracket 14 is so formed that the knitting head, together with the thread guides 5 and 8 and the knitting thread spools 7, is adapted to turn freely without interference with the rolls 11 and 12, the elastic thread 9 passing from between the rolls 11 and 12 directly downward to the guide 8, without requiring any intermediate guiding or holding means between the knitting head and the overhanging end of the bracket 14.

It should be noted that the rolls 11 and 12 are located above the substantial plan center of the knitting mechanism, with the horizontal axes of the rolls intersecting the vertical axis of rotation of the cylinder 3; this insures that the length of thread between the rolls 11 and 12 and the guide 8 remains unchanged as the guide 8 travels in its circumferential path with the cylinder 3.

The shaft 16 on which the lower roll 12 is mounted extends through the bracket 14 and is provided with a bevel gear 17 in mesh with a bevel gear 18 carried at the lower end of a vertical shaft 19 rotatably supported by the bracket 14. The shaft 19 is connected to a second vertical shaft 20 through pairs of bevel gears 21 and 22, and a shaft 23 extending horizontally across the top of the bracket 14. The lower end of the shaft 20 is connected by bevel gears 24 to a shaft 25 extending horizontally above the table 15 and rotatably supported between members 26 of a frame pivotally mounted on a cross rod 26^a.

The shaft 25 has mounted thereon a driving disk 27 which is in frictional engagement with a wheel 28 rotatably supported above the table 15 in a plane substantially at right angles to that of the disk 27. The wheel 28 is carried by a shaft 29 which extends downwardly below the table 15 and is connected by bevel gears 30 to a driving shaft 31 rotatably supported by the frame 32 which carries the table 15. The knitting head is also connected to the shaft 31 by any suitable gearing 33, so that the knitting head and the friction wheel 28 are adapted to be driven in unison, at the same speed, when the shaft 31 is rotated. A driving pulley 34 is mounted on the shaft 31 and is adapted to be connected thereto by means

of a suitable clutch 35. The clutch 35 is connected through suitable levers 36 to an operating rod 37, movement of which is adapted to control the operation of the machine, as will be hereinafter described.

Referring now to Figs. 3, 4 and 5, the disk 27 is provided with a hub 38 which is connected to the shaft 25 by a sliding keyway 39, and the hub 38 is embraced by the arms 40 of a shifting nut 41. The nut 41 is in threaded engagement with a screw shaft 42, rotatably supported above the wheel 28 between the uprights 26, and it is apparent that rotation of the shaft 42 will cause the nut 41 to be shifted bodily thereon and carry with it the disk 27. The position of the disk 27 on the wheel 28 with respect to the axis of rotation of the latter will obviously determine the speed of rotation of the shaft 25 for a given speed of rotation of the driving shaft 31, so that the speed at which the feed rolls 11 and 12 are driven will be determined by the position of the nut 41 on the screw shaft 42, and thus the rate of feed of the thread 9 is controlled solely by the position of said disk 27 relative to said wheel 28. The shaft 42 is extended beyond one upright 26 and is provided with a handle 43, see Fig. 2, whereby the shaft 42 may be turned manually; while it is provided beyond the other upright 26 with an operating head 44, whereby it may be automatically turned by mechanism which will now be described.

As best shown in Fig. 3, the shaft 31 is connected to a shaft 45 by gearing 46, so that the shaft 45 is driven at substantially the same speed of rotation as the friction wheel 28. A cam 47 is mounted on the shaft 45 and an arm 48, pivoted at 49, is provided with a roller 50 which is held in engagement with the cam 47 by means of a spring 51. The cam 47 is so formed that rotation of the shaft 45 will cause an oscillatory movement of the arm 48, the arm 48 being adapted to make one complete oscillation for each revolution of the knitting head and friction wheel 28. A pair of hooks 52 and 53 are pivotally mounted on brackets 54 and 55 carried by the upper end of the arm 48, the hooks 52 and 53 being each adapted to swing in a horizontal plane about vertical pivot pins 56 and 57, while the brackets 54 and 55 are pivoted about horizontal pins 54^a and 55^a. The hooks 52 and 53 are supported beyond the arm 48 on rods 58 and 59, so that as the arm 48 oscillates, the hooks 52 and 53 have imparted thereto a reciprocatory movement.

The hooks 52 and 53 extend from the arm 48 to a point adjacent the head 44 and the latter is provided with a number of radial pins 60 which are adapted to be engaged by either hook 52 or 53, should either of the latter be turned about its pivot pin 130

56 or 57. Hooks 52 and 53 are normally held in inoperative position shown in Fig. 4 by springs 52^a and 53^a, as shown in said figure. So long as the hooks 52 and 53 remain in the position shown in Fig. 4, it is obvious that they will not engage the pins 60, and in order to control the engagement of the hooks with the pins 60, I have provided an improved operating mechanism controlled from a pattern chain, as will now be described.

A bracket 61 extends upwardly from the table 15, and has pivotally mounted thereon a pair of operating levers 62 and 63 extending toward the hooks 52 and 53, respectively. The lever 62 is provided with an operating portion 64 having an inclined face 64^a for engaging the hook 52, while the lever 63 is provided with an operating portion 65 having an inclined face 65^a for engaging the hook 53. The levers 62 and 63 extend downwardly below the bracket 61, and terminate in arms 66, 67, embracing a sprocket wheel 68. Levers 62 and 63 are normally held in the upper position shown in Fig. 5 by means of springs 66^a and 67^a. The sprocket wheel 68 is rotatably mounted on a shaft 69 and is provided with a ratchet disk 70. The teeth 71 of the ratchet 70 are adapted to be engaged by a pawl 72 pivotally mounted on a pin 73 carried by an eccentric disk 74 mounted on the shaft 45. Rotation of the shaft 45 imparts a reciprocatory movement to the pawl 72, which in turn is adapted to impart a step-by-step rotative movement to the sprocket wheel 68, as the pawl 72 engages the ratchet teeth 71. The sprocket wheel 68 is therefore adapted to be turned through the angle subtended by one ratchet tooth 71 for each complete revolution of the friction wheel 28.

A pattern chain 75 passes over the sprocket wheel 68, with the teeth 76 of the latter engaging in the links of the chain, the number of teeth 76 corresponding to the number of ratchet teeth 71. The chain 75 is provided on either side thereof with projecting pins 77 and 78 which are adapted to engage the arms 67 and 66, respectively, of the levers 63 and 62, as the chain 75 is moved by the sprocket wheel 68. It is apparent from a consideration of Fig. 3 that when the arm 66 is engaged by a pin 78, the lever 62 will be turned in a clockwise direction and thereby cause the operating portion 64 to be moved downwardly with respect to the hook 52. When this occurs, the hook 52 is engaged by the face 64^a and is turned in the direction of the head 44, so that when the hook 52 is moved from left to right it will engage one of the pins 60, and thereby turn the head 44 in a clockwise direction through a distance equal to the angular spacing between the pins 60. Engagement of the pin 77 with the arm 67 of the lever 63 will cause

the operating portion 65 to move the hook 53 toward the head 44, and thereby cause the hook to engage a pin 60 and turn it in a direction opposite to the direction in which the head 44 is turned by the hook 52.

When the head 44 is turned by either hook 52 or 53, the screw shaft 42 will be turned a corresponding amount, with the result that the nut 41 will be shifted either to the right or to the left. The shifting movement of the nut 41 will cause the friction disk 27 to be moved either nearer to, or farther away from, the axis of rotation of the friction wheel 28, thereby resulting in either an increase, or decrease, in the speed of rotation of the shaft 25 which drives the elastic thread feed rolls 11 and 12. The timing of the mechanism is such that the disk 27 is shifted as a new course is about to be knit by the head, and it is obvious that the speed of the shaft 25, and therefore the speed of the rolls 11 and 12, will remain constant for any given position of the disk 27.

From the foregoing then it is apparent that the location of the pins 77 and 78 on the pattern chain 75 will determine the form of the tubular article which is knitted by the machine. Operation of pins 77 will cause the speed of the shaft 25 to be increased with a resultant increase in the speed of revolution of rolls 11 and 12, and thus in the amount of elastic thread fed and in the diameter of the fabric woven. Operation of the pins 78 will cause the speed of the shaft 25 to be decreased with a resulting decrease in the speed of revolution of rolls 11 and 12, and thus in the amount of elastic fabric fed and in the diameter of the fabric woven.

When it is desired to start the knitting machine in operation, the rod 37 is pushed to the right, thereby moving the clutch 35 through the levers 36 so as to connect the pulley 34 to the driving shaft 31. A spring 36^a normally tends to hold the clutch 35 out of engagement with the pulley 34, and the starting rod 37 is adapted to be locked in position so as to hold the clutch 35 in, by means of a latch 79 engaging in a notch 80 provided in the rod 37. As best shown in Fig. 3, the latch 79 is carried by a lever 81 pivoted at 82, so that the unbalanced weight of the lever 81 tends to hold the latch 79 in the notch 80 after the starting rod 37 has been moved far enough to the right to permit the latch to enter the notch.

The lever 81 extends between the arms 66 and 67, so that its lower surface just clears the pattern chain 75. The pattern chain 75 is provided with an upwardly extending stop 83 located at the end of the pattern, which stop 83 is adapted to engage the under surface of the lever 81 and raise the latter enough to disengage the latch 79 from the notch 80 in the arm 37. When this occurs, the spring 36^a acting through the levers 36,

throws the starting rod 37 to the left, thereby unclutching the pulley 34 from the shaft 31 and stopping the operation of the machine. In this way the machine is adapted 5 to be automatically stopped when an article has been completely knitted, as determined by the pattern chain, although it is obvious that the stop 83 can be placed at any desired point on the chain 75 so as to interrupt the knitting after a predetermined 10 length of fabric has been knitted. In order that the machine may be conveniently operated by hand, independently of the pulley 34, a handle 84 is provided, which is geared 15 to the shaft 31.

From the foregoing it is apparent that by my invention I have provided an improved mechanism for positively controlling the rotation of the rolls which feed the elastic 20 thread to the knitting head, whereby tubular knitted fabric may be produced having any desired shape. My improved mechanism is characterized by the fact that the elastic 25 thread feeding rolls operate independently of the rotation of the knitting head, so that the elastic thread passes directly from the feeding rolls to the head without necessitating the use of any auxiliary thread holding or guiding devices. Furthermore, the entire 30 mechanism for controlling the rotation of the elastic thread feed rolls, is supported on the table of the machine entirely apart from the knitting mechanism, so that the vibration attending the operation of the knitting 35 head is most unlikely to disturb the delicate adjustment of the feed roll controlling mechanism. Furthermore my feed rolls are adapted to feed the thread a fixed, definite 40 distance for each revolution thereof, the rate of thread feed being controlled solely by the speed regulating mechanism. Thus I avoid the employment of conical feed rolls for the 45 elastic thread, with the attendant uncertainties inherent therein, my thread feeding means being susceptible to quick, positive variation.

I claim:

1. In a machine of the class described, the 50 combination with a knitting mechanism comprising stationary sets of needles, a rotatable cam cylinder carrying thread guides and bobbins, and a supply of elastic thread stationary with respect to said guides, of a feed roll located above the substantial plan center 55 of said knitting mechanism, said feed roll being adapted to deliver a predetermined amount of elastic thread for each revolution of said roll, and a variable speed regulating mechanism located externally with respect 60 to said knitting mechanism for driving said roll.

2. In a machine of the class described, the 65 combination with a knitting mechanism comprising stationary sets of needles, a rotatable cam cylinder carrying thread guides

and bobbins, and a supply of elastic thread stationary with respect to said guides, of a rotatable member having an axis entirely outside of said knitting mechanism, a wheel frictionally driven at varying rates of speed 70 by said rotatable member, and a thread feeding roll driven by said wheel and located on a second stationary horizontal axis substantially intersecting the vertical axis of rotation of said knitting mechanism, and adapted 75 to feed the elastic thread to said knitting mechanism, with the rate of feed of the thread controlled solely by the position of said wheel relative to said rotatable member.

3. In a machine of the class described, the 80 combination with a knitting mechanism comprising stationary sets of needles, a rotatable cam cylinder carrying thread guides and bobbins, and a supply of elastic thread stationary with respect to said guides, 85 of variable speed regulating mechanism located externally to said knitting mechanism, a shaft driven by said regulating mechanism, thread feeding means located substantially above the plan center of said knitting 90 mechanism and removed from said shaft, said means comprising a member revolvable on a fixed axis, said member for each revolution being adapted to feed the elastic thread a predetermined unvarying distance, an idler 95 roll cooperating with and substantially tangent to said member, and driving mechanism for said thread feeding means adapted to drive said member at a fixed speed relative 100 to said shaft.

4. In a machine of the class described, the combination with a knitting mechanism comprising stationary sets of needles, a rotatable cam cylinder carrying thread guides and bobbins, a supply of elastic thread stationary with respect to said guides and a roll located above the substantial plan center 105 of the knitting mechanism for feeding the elastic thread, of a rotatably driven member having an axis entirely outside of 110 said knitting mechanism, a wheel in frictional engagement with said member adapted to drive said elastic thread feeding roll, a screw shaft on a stationary axis carrying a nut for shifting said frictional wheel on said rotatable member, and pattern controlled means for turning said screw shaft in either direction of rotation to shift said wheel and thereby vary the rate of rotation of said 115 elastic thread roll.

5. In a machine of the class described, the combination with a knitting mechanism comprising stationary sets of needles, a rotatable cam cylinder carrying thread guides and bobbins, a supply of elastic thread stationary with respect to said guides and a roll located above the substantial plan center 120 of the knitting mechanism for feeding the elastic thread, of a rotatably driven member having an axis entirely outside of 125

said knitting mechanism, a wheel in frictional engagement with said member adapted to drive said elastic thread feeding roll, a screw shaft on a stationary axis carrying a 5 nut for shifting said frictional wheel on said rotatable member, a pair of reciprocating elements turnable in the direction of said screw shaft, and pattern controlled means

for turning either of said elements to cause one of them to engage a projection on said screw shaft and turn the latter in either direction of rotation, whereby to shift the frictional wheel and vary the rate of feed of the elastic thread. 10

RICHARD M. FOSTER.
